UNITED STATES PATENT OFFICE.

LOUIS G. BEERS, OF TRENTON, NEW JERSEY, ASSIGNOR TO THE NEW JERSEY WIRE CLOTH COMPANY, OF TRENTON, NEW JERSEY, A CORPORATION OF NEW JERSEY.

WINDOW SCREEN.

Application filed April 12, 1927. Serial No. 183,040.

This invention relates to a novel window screen, the object of the invention being to provide a simple and cheap combination screen which will provide for proper ventilation under all conditions and at the same time protect against strong winds or extreme cold.

With these objects in view, the invention includes a window screen having combined therewith a smaller ventilating screen of finer mesh removable from the window screen, so as to permit the larger mesh portion of the window screen to be closed by the window, leaving the portion covered by the finer mesh ventilating screen open, the ventilating screen preferably carrying a closure which may be used to wholly or partially close the ventilating screen when desired.

In the accompanying drawings forming a part of this specification, the invention is illustrated in its preferred form, and this construction will now be discussed in detail and the features forming the invention then specifically pointed out in the claims.

In the drawings,—

Figure 1 is a face view of the window screen embodying all the features of the invention, and

Figure 2 is a perspective view of a portion of the ventilating screen.

Referring to the drawings, A is the window screen frame and *a* the comparatively open mesh wire screen therein, this window screen being the full depth for covering the whole or part of the window, as usual. Within frame A is removably mounted a ventilating screen frame B carrying the wire screen *b* of finer mesh than the screen *a*, this ventilating screen being shown as mounted to cover the entire width of a part of the window screen at its lower end and removably mounted in the frame A, simply being set within the frame and held in place by slides 1 mounted on frame B and entering holes in frame A. It will be understood, however, that this ventilating screen may be mounted at the top of the window screen if it be desired to ventilate through the upper part of the window.

This ventilating screen may be used alone

with the window screen, but preferably the 50 ventilating screen carries a swinging plate C of glass, but which may be of any other suitable material, preferably hinged on the bottom rail of frame B by hinges 2, as shown, so that the screen *b* may be wholly or partially 55 covered by the plate C, and the ventilating air from screen *b* directed upward into the room, as desired.

With my improved window screen, the window screens may be left in the windows throughout the year, being mounted so as to permit the window to slide up and down inside the screen, as usual, and the small ventilating screen be removed for free flow of air through the close mesh screen *a* during the 60 warm weather. In colder weather, the ventilating screen will be put in place in the window screen and its close mesh screen *b* will permit the room to be ventilated with a 65 less free flow of air, while the open mesh screen *a* is closed by the window. The flow of air through the close mesh screen *b*, also, can be prevented by closing the ventilating screen by plate C, or the air admitted through the screen *b* controlled as desired by the position 70 of plate C.

It will be understood that the invention is not limited to the specific construction illustrated for embodying the invention, but that modifications may be made therein while retaining the invention as defined by the claims.

What I claim is:

1. The combination with a window screen, of a ventilating screen frame removably mounted in the window screen frame and having screening material of finer mesh than the window screen, said ventilating screen extending vertically over only a portion of the window screen at one end of the window.

2. The combination with a window screen, of a ventilating screen frame extending over the entire width of only a portion of the window screen at the lower end of the window and having screening material of finer mesh than the window screen, said ventilating screen frame being removably mounted in the window screen frame.

3. The combination with a window screen,

of a ventilating screen frame extending over the entire width of only a portion of the window screen at the lower end of the window and having screening material of finer mesh than the window screen, said ventilating screen being removably mounted in the window screen frame and a cover hinged

at the lower side of the ventilating screen and adapted to close the ventilating screen or direct the air upward at the angle desired. ¹⁰
In testimony whereof, I have hereunto set my hand.

LOUIS G. BEERS.
